PREVENTING CORROSION OF METALS

Cecil Phillips, Jr., Baytown, Tex., assignor, by
mesne assignments, to Standard Oil Develop-
ment Company, Elizabeth, N. J., a corporation
of Delaware

No Drawing. Application June 20, 1947,
Serial No. 756,112

5 Claims. (Cl. 23—193)

1

This invention is directed to a method for sup-
pressing the corrosion of copper-containing
alloys in the presence of ammonia. Specifically,
it is directed to the prevention of corrosion of
copper alloys in aqueous solutions containing
ammonia.

In many operations it is often desirable to use
various types of equipment (tanks, heat ex-
changer and condenser tubes, valves, lines, etc.)
constructed of or containing copper alloys for
handling solutions or gases containing ammonia.
Such equipment usually suffers from severe cor-
rosion of the copper alloys due to the chemical
dissolution of the copper by the ammonia. The
rapid destruction of the copper alloys in con-
tact with solutions or vapors containing ammonia
is believed to be due to the formation of highly
soluble copper-ammonium complex ions. The
presence of oxygen is necessary for the forma-
tion of the soluble copper-ammonium ions.

As a result of the corrosive action of ammoni-
acal solutions on copper, the employers of am-
monia, such as the petroleum refiner, must ex-
ercise extreme care in selection of suitable alloys
for his processing equipment. Thus, where am-
monia is to be used, copper alloys are avoided.
However, as mentioned before, various services
require the use of copper alloys on account of
other corrosive fluids being encountered. Thus
the corrosive action of carbon dioxide in steam
makes nearly mandatory the employment of
copper alloys such as an alloy of copper, zinc,
and tin in heat exchange equipment using cor-
rosive steam as the heat transfer medium. Thus,
when ammonia is employed in this type of equip-
ment, rapid attack of the copper alloy may be
suffered even though the ammonia may prevent
attack of ferrous metals by other components
travelling through the equipment. Ammoniacal
solutions are also widely used in solvent extrac-
tion of hydrocarbons. Here, again the petroleum
refiner must guard against allowing the solutions
to contact copper-bearing surfaces. The afore-
mentioned corrosion reaction generally occurs at
atmospheric temperature and pressure. It is
believed that higher temperatures and pressures
may accelerate this reaction.

It is, therefore, the main object of the present
invention to provide a process whereby the
deterioration of copper alloys in the presence of
ammonia is substantially eliminated.

Another object of the invention is to provide
a method whereby copper alloys may be em-
ployed in services where they are exposed to
ammoniacal solutions.

The objects of the present invention are
achieved by maintaining in corrosive ammoniacal
solutions in contact with copper and its alloys
a corrosion inhibiting amount of a salt of a
petroleum sulfonic acid.

Briefly, the present invention involves the

2

addition to corrosive ammoniacal solutions in
contact with copper bearing metals of a quantity
of a salt of petroleum sulfonic acid, such as an
alkali metal salt of petroleum sulfonic acid, in the
range between 0.001% to 5% by weight, based
on the ammoniacal solution.

The salts of petroleum sulfonic acid which are
suitable for use in the practice of the present
invention are the alkali metal salts of petroleum
sulfonic acids, such as the lithium, sodium, or
potassium salts. The ammonium salts of petro-
leum sulfonic acids are also eminently suitable
in the practice of the present invention.

The petroleum sulfonic acids which are em-
ployed to produce the salts used in the present
invention may be obtained in a manner well
known to the art. The production of mahogany
sulfonic acids has been disclosed widely in patent
literature. However, a conventional method for
preparing these acids involves the treatment with
concentrated sulfuric acid of a feed stock com-
prising a substantial portion of unsaturated cyclic
hydrocarbons. Exemplary of the type of feed
stocks which may be used are the solvent extracts
resulting from solvent extraction of a distillate
boiling in the lubricating oil boiling range, such
as, for example, a phenol extract. The extract
layer, upon treatment with strong sulfuric acid
results in the formation of a layer comprising
oil and oil soluble sulfonic acids or mahogany
acids, and a second layer comprising sludge par-
ticles and water-soluble sulfonic acids. These
two layers are then separated under the influ-
ence of gravity and the oil layer, including
mahogany acids, is treated with successive por-
tions of water to obtain the predominately oil
soluble sulfonic acids. These oil soluble sulfonic
acids may be freed of water and then converted
into the corresponding salts by addition of sodium
hydroxide or ammonium hydroxide if desired.
As a specific example, a distillate obtained from
a naphthenic crude oil may be solvent extracted
with a solvent having the characteristics of fur-
fural or phenol and the extract brought in con-
tact with sulfuric acid of approximately 98%
concentration. Upon contacting the concen-
trated sulfuric acid with the petroleum extract,
sulfonic acids are formed. The mahogany acids
remain in the oil phase which separates from the
acid phase.

In applying the concentrated sulfuric acid, it
is customary to divide the total amount em-
ployed into a number of portions and treat the
petroleum extract separately with each portion
and the mahogany acids allowed to remain in
the extract phase or separated, if desired, be-
tween each treat with sulfuric acid. Preferably
the oil soluble sulfonic acids or mahogany acids
are obtained from the acid treated extract after
each portion of sulfuric acid has been added
thereto.

The mechanism by which the alkaline salts of petroleum sulfonic acids are effective in preventing the corrosion of copper alloys by ammonia is not understood, but it is believed to be due to the formation of a very thin protective film on the metal. It is understood, of course, that I do not wish to bind myself to any theory offered as an explanation of the beneficial effect.

An advantage of the process of the present invention, irrespective of the prevention of corrosion of copper and its alloys, is the ability to use existing equipment in which copper and its alloys are present in processes involving the use of ammonia.

In order to illustrate the beneficial effects of this invention, specimens of copper-containing metal (70% copper, 29% zinc, and 1% tin) were immersed in aqueous solutions of ammonia. These tests were in progress for 24 hours at room temperature and atmospheric pressure. Air was bubbled through the ammonia solutions throughout the tests. These tests were repeated under identical conditions with small amounts of sodium sulfonates of petroleum sulfonic acids of the type illustrated added to the aqueous solutions of ammonia. The results obtained in these tests are shown in the following table:

Ammonium Hydroxide Solution	Material Added	Wt. Per Cent Based on Ammonia Sol'n	Corrosion Rate, Inch per year	Per Cent Reduction
5% by wt.	None		0.1425	
Do.	Sodium Sulfonates	1.0	0.0682	52.1
Do.	Sulfonates of Petroleum Hydrocarbons.	0.5	0.0268	81.2
Do.		0.25	0.0753	47.2

It will be observed from the data presented in the foregoing table that the addition of small amounts of sodium salts of petroleum sulfonic acids effects marked reductions in the tendencies of aqueous solutions of ammonia to corrode copper-containing alloys.

Another series of runs identical to those described in the foregoing paragraph was conducted in which specimens of the same type of copper-containing metal were immersed in aqueous solutions of ammonia to which were added small amounts of ammonium sulfonates of mahogany acids from petroleum. All conditions in this series of runs otherwise were identical to the series of runs in which sodium sulfonates of mahogany acids were employed. The results obtained in these runs are shown in the following table:

Ammonium Hydroxide Solution	Material Added	Wt. Per Cent Based on Ammonium Sol'n	Corrosion Rate, Inch per year	Per Cent Reduction
5% by wt.	None		0.1425	
Do.	Ammonium Sulfonates	0.5	0.01720	88.0
Do.	Sulfonates of Petroleum Hydrocarbons.	0.25	0.0346	75.7
Do.		0.05	0.0418	70.6

It will be observed from the data presented in the foregoing table that the addition of small amounts of ammonium salts of petroleum sulfonic acids effects marked reductions in the tendencies of aqueous solutions of ammonia to corrode copper-bearing alloys.

The present invention has been described and illustrated as inhibiting the corrosive effect of solutions in ammonia and water. It is understood that the invention has broad application in the inhibition of corrosive action of an ammoniacal solution such as ammonia and water to copper-bearing metals. The invention may be applied to the inhibition of the corrosive effects of aqueous solutions of ammonium salts. For example, ammonium acetate is widely used in the petroleum refinery as a solvent. It is known that ammonium acetate will attack copper-bearing metals quite readily. Therefore, it is within the spirit and scope of the invention to inhibit the corrosiveness of ammonium salt solutions to copper-bearing metals employing salts of mahogany acids as the inhibitor.

The nature and objects of the present invention having been fully described and illustrated, what I wish to claim as new and useful and to secure by Letters Patent is:

1. A method for reducing the corrosive action of a corrosive solution including ammonia, water, and oxygen to an article having a corrodible surface consisting of copper, tin, and zinc in contact with said solution which comprises introducing into said solution an amount of a salt of a petroleum mahogany acid sufficient to inhibit the corrosion thereof.
2. A method in accordance with claim 1 in which the amount of salt of mahogany acids is in the range between 0.001% and 5% by weight of the corrosive solution.
3. A method in accordance with claim 1 in which the salt of mahogany acid is a sodium salt.
4. A method in accordance with claim 1 in which the salt of mahogany acid is a potassium salt.
5. A method in accordance with claim 1 in which the salt of mahogany acid is an ammonium salt.
